AMUSEMENT DEVICE

Frank M. Pierce, Miami, Fla.

Application October 18, 1935, Serial No. 45,595

15 Claims. (Cl. 273—138)

My invention relates to amusement devices and particularly to a structure comprising a housing or cage having a plurality of shelves therein, together with projector means manually operable from the exterior of the cage for throwing counting members such as dice upwardly in the cage to land on the shelves, the scoring being determined by the arrangement of the counting members on the shelves.

10 A feature of the invention is the provision of shelves of different colors and counting members of corresponding colors with the scoring depending upon projected counting members landing on correspondingly colored shelves.

15 Another feature of the invention is the inclusion among the counting members of an elongated preferably tubular member, as for example a thimble, with the landing of the thimble on a shelf, whether on its side or on end, having a 20 certain value in the determination of the score.

25 A further feature of the invention is the provision of a unitary shelf structure in the form of a stepped plate with the steps forming the shelves, and with the shelf structures pivotally mounted for swing or rotation thereof to dump the accumulated counting and scoring members.

30 A further feature of the invention resides in improved projection means in the form of a projection lever extending along the bottom of the cage for supporting the counting members at its inner end so that a downward blow on its outer end will cause the counting members to be thrown upwardly in the cage for landing on the shelves.

35 The above enumerated and other features of the invention are embodied in the structure shown on the drawing, in which drawing

Figure 1 is a plan view of the device; and

40 Figure 2 is a section on plane II—II of Figure 1.

45 The structure shown comprises the elongated rectangular base 1 whose inner portion has the rearwardly inclined top 2. A housing is mounted on and secured to the base 1 and may be in the form of a cage comprising an arch shaped wall 3 forming the front and rear sides and the top of the cage, and the side wall structures 4 which may be in the form of wire netting, which netting may be secured to the inwardly deflected portions or flanges 5 on the wall 3. The top portion of the wall 3 may be provided with longitudinally extending slots 6 so that through these slots and the wire mesh sides 4, the interior of the cage may be fully visible at all times.

50 At approximately the central point of the mesh side walls 4, these walls have bearing plates 7

secured thereto for journaling a shaft 8 which is secured to the rear end of a shelf structure 9 which, when in its normal position, extends forwardly to the front part of the wall 3, the shelf structure normally resting on a stop 10 which may be in the form of a sheet metal strip secured to and extending between the mesh side walls 4. Between the side walls 4 and the adjacent edges of the shelf structure, washers 11 of suitable material are mounted on the shaft 8 so as to keep the shelf structure clear at its edges from the 10 side walls 4. The outer ends 12 of the shaft are deflected at right angles to afford handles by means of which the shelf structure may be swung upwardly to dump accumulated counting members therefrom after a playing operation, and the extent of such dumping movement is limited by the engagement of one of the handle ends with a stop 13 extending from one of the side walls 4. The shelf structure may be in the form of a single plate of sheet metal deflected to form the step or shelf portions A, B and C, and these shelf portions may have their top surfaces of different colors, as for example, red, white and blue, respectively.

20 The projector mechanism shown comprises an elongated rectangular plate or board 14 which is pivoted intermediate its ends on the base 1. To provide such pivot support, a U-shaped yoke frame 15 may be screwed or otherwise secured against the underside of the projector board with its depending ends engaging pivot screw 16 secured in the base 1 which may be of wood or formed of sheet metal, as desired. The pivot support of the board is adjacent to the front end of the inclined top 2 of the base, the board extending rearwardly to within a short distance of the rear part of the wall 3 and is normally held in inclined position by a thrust spring 17 seated in a pocket 18 provided in the base and engaging against the under side of the projector plate in front of the plate pivot axis, the top surface 2 of the base having preferably a cushion abutment 19 thereon for engagement by the inner end of the projector board.

25 The front end of the projector board extends to the exterior of the cage through an opening 20 provided in the front part of the wall 3, and on this outer end of the board an impact cushion 21, which may be of sponge rubber, is secured which cushion is struck by the fist or the hand for quick upward swing of the rear end of the board and upward projection of counting members normally supported by the board. The 30 counting members 22 are preferably in the form of cubes or dice and for supporting the counting 35

members on the projector board a sheet metal frame of angular cross section is mounted on the board 14 above the rear portion thereof. This supporting frame may be formed from a single 5 piece of sheet metal and comprises the wall parts 23, 24 and 25, the wall 24 extending upwardly at right angles with the wall 23, the wall 23 resting at its rear end against the rear end of the board 14 and being held tilted away from the 10 board 14 by the front wall 25, the supporting structure being held in place as by screws 26 extending through the wall 25 and into the board 14. The walls 23 and 24 may be lined by cushioning material 27 such as felt.

15 The counter members 22 may be plain cubes or game dice and are preferably of different colors, as for example, red, white and blue, to correspond with the coloring of the shelves A, B and C. The counting members normally rest on the 20 support wall 23 against the back wall 24 thereof, and to avoid interference of the side walls 4 with the counting members, guide or guard walls 28 may be extended upwardly from the supporting wall 23 in front of the back wall 24.

25 In playing the game, the projector lever is suddenly swung by a blow against the outer end thereof, as by the fist. The counting members are then thrown upwardly and forwardly to land on the shelves A, B and C, the score depending 30 upon the matching of the colored counting members with the colors of the shelves on which they land, a count of ten being recorded for each cube that lands on a shelf of similar color. A count of 30 will be registered if all three cubes land 35 on the same shelf. After each play the shelf structure is swung upwardly to dump the accumulated counters therefrom. To make the game more interesting, an odd or roving counting member of elongated or tubular form, such as a 40 thimble 29 may be added. The game could be that when the thimble lands on any shelf on its side it would not count in the scoring, but if the thimble landed on either end it would put the player "out".

45 A tiltable and preferably removable shelf 30 is also provided to be extended between the side walls 4 in the path of projected counters, the scoring depending on the number of counters which can be landed on top of the shelf. For example, the winner would be the one who first 50 landed all three cubes, or all three cubes plus the thimble, on the shelf 30, this requiring considerable skill as the thimble is lighter than the cubes and more or less interferes with the landing of 55 the cubes.

Where game dice are used, the scoring could further depend on the numbers displayed by the dice after landing on the shelves.

To eliminate noise and stop the impact of the projector board when it is struck downwardly, a cushion 31 preferably of sponge rubber is secured on the base 1 below the projector board. The front end of the base 1 may be hollow to provide a receptacle 32.

60 I have shown a practical and efficient embodiment of the various features of my invention, but I do not desire to be limited to the exact construction, arrangement and operation shown and 65 described as changes and modifications may readily be made without departing from the scope and spirit of the invention.

67 I claim as follows:

68 1. In a device of the class described, a housing, 70 a projection lever pivoted intermediate its ends 75

said housing and projecting to the exterior thereof to be struck for upward throw of the inner end thereof, supporting means on the inner end of said lever for counting members, shelves within said housing, said counting members being differently colored and said shelves being individually colored to correspond with the coloring of 5 said counting members.

2. In a device of the class described, a housing, 10 a projection lever pivoted intermediate its ends and extending along the bottom of the housing with its outer end projecting to the exterior of the housing to be struck for upward swing of the inner end of the lever, supporting means on the inner end of said lever for counting members, a 15 shelf structure within said housing providing a series of shelves for receiving the projected counting members when said lever is operated, said shelf structure being hinged to be swung for dumping therefrom of the accumulated counting 20 members.

3. In a device of the class described, a housing, 25 a projection lever extending along the bottom of said housing with its outer end projecting to the exterior of the housing to be struck downwardly for upward swing of the inner end of the lever, a support on the inner end of said lever for counting members, a shelf structure within said housing providing a plurality of shelf surfaces for receiving projected counting members when said lever 30 is operated, said shelf structure being arranged to be swung for dumping collected counting members therefrom back onto said support.

4. In a device of the class described, a housing, 35 a projection lever extending along the bottom of said housing with its outer end at the exterior thereof to be struck downwardly for upward swing of the inner end of the lever, a support on the inner end of the lever, a plurality of counting members comprising a number of cubes and a 40 tubular member, said counting members normally resting on said support for upward projection thereof in said housing when said lever is operated, and shelving within said housing for receiving projected counting members, said shelving 45 being arranged to be manually moved for dumping received counting members therefrom back to said support.

5. In a device of the class described, the combination of a cage structure, a projection lever 50 extending along the bottom of said cage with its outer end projecting to the exterior thereof to be struck downwardly for upward swing of the inner end of the lever, a support at the inner end of said lever, a plurality of counting members 55 comprising a number of cubes and a thimble, said counting members normally resting on said support, shelves in said cage structure equal in number to the number of cubes for receiving the projected cubes or the thimble when the lever is 60 operated, said cubes being differently colored and said shelves being correspondingly colored.

6. In a device of the class described, a housing, 65 a projection lever pivoted intermediate its ends and extending along the bottom of the housing with its outer end projecting to the exterior of the housing to be struck for upward swing at the inner end of the lever, supporting means on the inner end of said lever for counting members, a shelf structure within said housing providing a 70 series of shelves for receiving the projected counting members when said lever is operated, said shelf structure being hinged to be swung for dumping therefrom of the accumulated counting members, and a removable shelf in said housing 75

above said pivoted shelf structure for receiving projected counting members.

7. In a device of the class described, a housing, a projection lever pivoted intermediate its ends 5 and extending along the bottom of the housing with its outer end projecting to the exterior of the housing to be struck for upward swing at the inner end of the lever, supporting means on the inner end of said lever for counting members, upper and lower shelf structures within said housing for receiving projected counting members, said shelf structures being tilttable in directions for dumping accumulated counting members therefrom back to said supporting means.
- 15 8. In a device of the class described, a housing, a projection lever extending into said housing from the exterior thereof and adapted to support counting members, and shelving within said housing for receiving projected counting members 20 when said projection lever is operated, said counting members being differently colored and said shelving having surfaces colored to correspond with the coloring of said counting members.

9. In a device of the class described, a cage 25 structure, a projecting lever extending into said cage structure from the exterior thereof and adapted for supporting counting members within said cage structure, shelving within said cage structure for receiving projected counting members when the lever structure is operated, and means supporting said shelving for dumping movement thereof to return received counting members to said lever.

- 30 10. In a device of the class described, a housing, a projection lever extending along the bottom of said housing with its outer end at the exterior of the housing for manipulation thereof, a plurality of counting members comprising a number of cubes and a tubular member, said counting members normally resting on said lever for upward projection thereof in said housing when said lever is operated, and shelving within said housing for receiving projecting counting members, said shelving having differently colored 45 surfaces.

11. In a device of the class described, a housing, a projection lever extending across the bottom of said housing with its manipulating end at the exterior of the housing, said lever having pivotal 50 support intermediate its ends within said housing and adapted to support counting members at one side of the housing for upward projection

in said housing when said lever is manipulated, and shelving supported at the opposite side of said housing for receiving projected counting members.

12. In an amusement device of the class described, a housing, a projection lever extending across the bottom of said housing with its front end outside of the housing for manipulation thereof, means pivoting said lever within said housing near the front thereof, said lever at its 10 inner end being adapted to support counting members adjacent the rear wall of said housing, and shelving at the front part of said housing above said lever for receiving projected counting members.

15 13. In an amusement device of the class described, a housing, a projection lever extending across the bottom of said housing with its front end outside of the housing for manipulation thereof, means pivoting said lever within said 20 housing near the front thereof, said lever at its inner end being adapted to support counting members adjacent the rear wall of said housing, and shelving at the front part of said housing above said lever for receiving projected counting 25 members, and means supporting said shelving for dumping movement thereof to return received counting members to the rear end of said lever.

14. In an amusement device of the class described, a housing, a projection lever extending 30 into said housing from the exterior thereof and arranged for manipulation to project counting members therefrom upwardly through said housing, and upper and lower shelf structures within said housing for receiving projected counting 35 members, said shelf structures being tilttable in direction for dumping accumulated counting members therefrom back to said lever.

15. In a device of the class described, a housing, a lever extending into said housing from the 40 exterior thereof and arranged for manipulation to project counting members therefrom upwardly in said housing, shelving within said housing above said lever, said shelving comprising an upper shelf structure and a lower shelf structure 45 for receiving projected counting members, said shelf structures being tilttable in direction for dumping accumulated counting members therefrom back to said lever, said shelving having differently colored surfaces.

50 FRANK M. PIERCE.
